UNITED STATES PATENT OFFICE.

HENRI HATTOY, OF BLACKSTONE, MASSACHUSETTS, ASSIGNOR TO CROMPTON & KNOWLES LOOM WORKS, OF WORCESTER, MASSACHUSETTS, A CORPORATION OF MASSACHUSETTS.

LOOM DOBBY.

Application filed March 22, 1923. Serial No. 626,778.

To all whom it may concern:

Be it known that I, HENRI HATTOY, a citizen of the United States, residing at Blackstone, in the county of Worcester and State of Massachusetts, have invented a new and useful Loom Dobby, of which the following is a specification.

This invention relates to a loom dobby of the general type shown in the prior patent, 10 to Selley No. 955,559, issued April 19, 1910. This patent discloses a dobby having a lower or main pattern cylinder and an upper or auxiliary cylinder, the dobby being particularly designed for weaving 15 handkerchiefs, towels or other similar articles in which an end border is inserted at frequently occurring points in the length of the fabric.

It is the object of my invention to improve 20 the construction of dobbies of this general type by providing novel devices for connecting the upper and lower dobby fingers. My improved connections not only accomplish the necessary associated movements of the dobby fingers but also act as guides for the fingers, thereby reducing the 25 number of guide pins heretofore specially provided for this purpose.

My invention further relates to arrangements and combinations of parts which will be hereinafter described and more particularly pointed out in the appended claims.

A preferred form of the invention is shown in the drawings in which

35 Fig. 1 is a side elevation of parts of a dobby embodying my improvements;

Fig. 2 is a sectional side elevation of the dobby;

Fig. 3 is a detail end elevation thereof;

40 Fig. 4 is a detail sectional plan view, taken along the line 4—4 in Fig. 3; and

Fig. 5 is a partial detail view of one of my improved links or connectors.

Referring to the drawings, I have shown 45 parts of a dobby which is in general of the construction shown in the prior patent to Selley and comprises a frame 10 supporting a lower or main pattern cylinder 11, an upper or auxiliary pattern cylinder 12, and 50 a rocking lever 13 mounted on a fixed pivot 14. The dobby is provided with the usual series of lower dobby fingers 15 and upper dobby fingers 16, these fingers being controlled by pattern chains on the cylinders 55 11 and 12 respectively. A single bar 17 and

pin 18 of the lower pattern chain and corresponding parts 19 and 20 of the upper pattern chain are indicated in Fig. 2.

A ratchet 21 (Fig. 1) is fixed to the lower pattern cylinder 11 and is engaged by a feed pawl 22 pivoted at 23 to the rocking lever 13. A stud 24 in the side of the pawl 22 rests on a link or rod 25 which is supported at one end on a projection 26 on the side of a special lower dobby finger 15^a. The opposite end of the link 25 has a slotted connection with a pin 27 in a lever 28 mounted on a fixed pivot 29 and connected by a link 30 to a lever 31 pivoted at 32 in the upper part of the dobby frame. 70

This upper lever 31 has a projection 33 which cooperates with a special pattern chain 34 on the end of the upper cylinder 12. The parts are so proportioned that when in the position shown in Fig. 1 the pawl 22 will actuate the lower or main cylinder 11 to weave the body of the handkerchief or other fabric. If, however, the dobby finger 15^a is raised by a pin, such as 18, in the lower pattern chain, the link 25 will be swung about one end on the stud 27 and will engage the stud 24 in the pawl 22, raising the same out of operative position. At the same time, the upper pattern cylinder will be started in operation by 75 feeding mechanism not shown and will proceed to weave a border or other special design. At the same time, the upper pattern cylinder will be started in operation by 80 feeding mechanism not shown and will proceed to weave a border or other special design. At the same time, the upper pattern cylinder will be started in operation by 85 feeding mechanism not shown and will proceed to weave a border or other special design. At the same time, the upper pattern cylinder will be started in operation by 90 feeding mechanism not shown and will proceed to weave a border or other special design. At the same time, the upper pattern cylinder will be started in operation by 95 feeding mechanism not shown and will proceed to weave a border or other special design. At the same time, the upper pattern cylinder will be started in operation by 100 feeding mechanism not shown and will proceed to weave a border or other special design. At the same time, the upper pattern cylinder will be started in operation by 105 feeding mechanism not shown and will proceed to weave a border or other special design. At the same time, the upper pattern cylinder will be started in operation by 110 feeding mechanism not shown and will proceed to weave a border or other special design.

My invention relates specifically to the connections between the lower dobby fingers 15 and the associated upper fingers 16. For this purpose, I provide the links 40 (Fig. 3) each link having a reverse bend 41 at its upper end and having an offset projection 42 (Fig. 5) at its lower end.

In assembling my improved links or connectors, I preferably arrange them in pairs 110

to slide in recesses 43 in fixed cross bars 44, as indicated in Fig. 4. Each pair is separated from the next pair by two dobby fingers 15 of the lower set and by two fingers 16 of the upper set. The bent upper ends 41 are turned in opposite directions so that they each engage the upper edge of one of the pair of adjacent fingers 16 and the projections 42 are correspondingly reversed 10 and each project under one of the associated pair of lower fingers 15.

Fixed guide pins or rods 45 alternate with the links 40, as shown in Fig. 4, so that each finger is guided on each side by a link 40 15 or by a special guide pin 45.

With this construction, the lower fingers 15 may be moved upward without moving the links 40, as the fingers merely rest upon the upper portions of the projections 42. 20 Whenever an upper finger 16 is raised, however, the corresponding lower finger 15 is also raised, this associated movement being necessary for the operation of the dobby. It will thus be seen that I have provided a 25 connection in which the links move only when the upper fingers move and that I have reduced the number of parts by utilizing the links as guides between alternate fingers.

Having thus described my invention and 30 the advantages thereof, I do not wish to be limited to the details herein disclosed otherwise than as set forth in the claims, but what I claim is:—

1. In a loom dobby, a main pattern cylinder, an auxiliary pattern cylinder, upper and lower dobby fingers co-operating with said cylinders respectively, and links connecting said upper and lower fingers in pairs, each lower finger being movable upward by its pattern cylinder while the associated link and upper finger remain at rest. 40

2. In a loom dobby, a main pattern cylinder, an auxiliary pattern cylinder, upper and lower dobby fingers co-operating with 45 said cylinders respectively, and links connecting said upper and lower fingers in pairs, each link being connected to an upper lever for upward movement therewith and having a projection underlying the associated lower finger. 50

3. In a loom dobby, a main pattern cylinder, an auxiliary pattern cylinder, upper and lower dobby fingers co-operating with 55 said cylinders respectively, and links connecting said upper and lower fingers in pairs, each link forming a lifting connection

from an upper finger to an associated lower finger but leaving said lower finger free to move upward independently of said link and upper finger. 60

4. In a loom dobby, a main pattern cylinder, an auxiliary pattern cylinder, upper and lower dobby fingers co-operating with said cylinders respectively, and links connecting said upper and lower fingers in 65 pairs, each link having a return bend at its upper end embracing an upper finger and having an offset projection in its lower portion extending under the associated lower finger. 70

5. In a loom dobby, a main pattern cylinder, an auxiliary pattern cylinder, upper and lower dobby fingers co-operating with said cylinders respectively, and links connecting said upper and lower fingers in 75 pairs, said links being vertically slidable in fixed upper and lower members and forming separating guides for said fingers.

6. In a loom dobby, a main pattern cylinder, an auxiliary pattern cylinder, upper 80 and lower dobby fingers co-operating with said cylinders respectively, and links connecting said upper and lower fingers in pairs, said links being mounted in pairs for sliding movement in fixed upper and lower members and engaging the upper and lower fingers at each side of said links. 85

7. In a loom dobby, a main pattern cylinder, an auxiliary pattern cylinder, upper 90 and lower dobby fingers co-operating with said cylinders respectively, and links connecting said upper and lower fingers in pairs, said links being vertically slidable in fixed upper and lower members and being disposed in pairs between alternate fingers, 95 also constituting guides therefor on one side of each finger.

8. In a loom dobby, a main pattern cylinder, an auxiliary pattern cylinder, upper and lower dobby fingers co-operating with 100 said cylinders respectively, links connecting said upper and lower fingers in pairs, said links being vertically slidable in fixed upper and lower members and being disposed in pairs between alternate fingers, also constituting guides therefor on one side of each finger, and a series of fixed guide pins alternating with said links and engaging the opposite sides of said fingers. 105

In testimony whereof I have hereunto affixed my signature.

HENRI HATTOY.
